UNITED STATES PATENT OFFICE

2,210,829

CONE DISPENSER

James Balton, Baltimore, Md., assignor to Maryland Baking Company, a corporation of Maryland

Application August 19, 1938, Serial No. 225,826

1 Claim. (Cl. 312—43)

My invention relates to devices for dispensing cones from the cartons in which they are shipped, and it has for its primary object to provide a sample apparatus that can be cheaply manufactured and yet one that will be strong and durable and effectively serve the intended purpose.

Other objects will in part be obvious and in part be pointed out hereinafter.

To the attainment of the above objects and ends the invention still further resides in those novel features of construction, combination and arrangement of parts, all of which will be first fully described in the detailed description and then be particularly pointed out in the appended claim, reference being had to the accompanying drawing, in which:

Fig. 1 is a top plan view of a dispenser for dispensing cones from cellular containers having provisions for ten stacks of cones.

Fig. 2 is a vertical longitudinal section on the line 2—2 of Fig. 1.

Fig. 3 is a detail section on the line 3—3 of Fig. 1.

In the drawing, in which like numbers of reference indicate like parts in all the figures, 1 is the front wall and 2 the end walls which are stamped from a single sheet, the ends of which are curled, as at 3, to constitute sockets to receive the rods 26 of a suitable stand for supporting the device if desired.

The back wall 4 has side flanges 5 which are spot welded to the sides 2 and it also has an offset 6 and a hanger 7 with key-hole slots 8 by which the device may be mounted on a wall when a stand is not used.

The bottom of the dispenser comprises gates (one or more, depending on the size of the device) 9—10—11 hinged to the back wall 4, as at 22, and having spring tongues 13 to snap over the bulges 40 or ribs 12 formed in the bottom edge of the front wall 1. The several walls have vertical and horizontal tongues 14 and 15 respectively to hold advertising cards (not shown).

A plate 16 having flanges 18 spot welded, as at 19, to the front and back walls divides the container formed by the walls 1, 2 and 4 and gates 9—10—11 into an upper and a lower compartment. The plate 16 has holes 17 to register with the several stacks of cones to be dispensed. Leaf spring fingers 20 are riveted at 21 to the plate 17 to engage the lowermost cones in the stacks and hold the stacks against accidental

discharge of the cones, but yielding sufficiently to allow one to pull out the bottom cone from the stack when desired.

The carton 23 in which the cones are shipped (indicated at 25 in dotted lines in Fig. 2) have longitudinal and cross partitions 23 and 24 to form the pockets in which the cone stacks are located. These cartons have closure flaps at each end and when the dispenser is to be used the carton is opened at the bottom and the box or frame 10 of the dispenser is made to receive the open end of the carton which rests on the plate 17. With the gates 9—10—11 closed the cones 27 rest on the gates, but when a gate is opened (see 18, Fig. 2), the stack or stacks of cones above the gate drop down until caught by the fingers 20 where they remain until taken out one at a time by pulling down on the exposed cone.

The top of the carton being left closed, dust and dirt are kept from depositing on the cones in 20 the carton, and when gates 9—10—11 are closed a substantially dust-proof enclosure for the cones is obtained.

While I have shown the dispenser designed to dispense cones from cartons carrying ten stacks, 25 it will be an obvious modification to design it for cartons containing a lesser number of stacks than ten.

From the foregoing description, taken in connection with the accompanying drawing, it is thought that the construction and advantages of the invention will be clear to those skilled in the art to which it relates.

What I claim is:

A dispenser for cones in cellular cartons in which the cells are arranged in a plurality of longitudinal and transverse groups, comprising a shallow frame formed to receive an open end of the carton, a horizontal partition in said frame and supported thereby, on which the carton may rest, said partition having cone passing holes corresponding in number and position to the cells in the carton, a set of leaf spring fingers for each hole secured individually to and depending from said partition under said holes for holding the stacks of cones against accidental discharge when the bottom of the dispenser is open, a plurality of gates hinged along one side of the frame, and means to hold the gates closed and thereby lift the cones out of contact with said fingers. 50

JAMES BALTON.
